UNITED STATES PATENT OFFICE.

GILBERT S. WALKER, OF BROOKLYN, NEW YORK.

AUTOMATIC WATER-HEATER.

1,330,362.

Specification of Letters Patent. Patented Feb. 10, 1920.

Application filed August 14, 1915. Serial No. 45,511.

To all whom it may concern:

Be it known that I, GILBERT S. WALKER, a citizen of the United States, residing at Brooklyn, in the county of Kings and State 5 of New York, (whose post-office address is % American Society Mechanical Engineers, 29 West 39th St., New York, N. Y.,) have invented a new and useful improvement in Automatic Water-Heaters, of which im- 10 provement the following is a specification.

My invention relates to improvements in automatic water heaters.

The primary object of my invention is to produce a device whereby the flow of water 15 is automatically controlled by the thermostat and also to control the flow of gas to the burners in a simple manner.

One of the advantages of my invention is economizing the consumption not only of 20 gas but also of water. An additional advantage is that the two sides of the piston being in direct communication respectively with the cold water inlet and the hot water outlet, the friction of the coils is utilized in 25 operating the piston, thus reducing the total loss of head through the heater.

In the accompanying drawings I show one embodiment of my invention, in which—

Figure 1 is a side elevation of the device 30 applied to a heater, part of the shell being removed.

Fig. 2 is a sectional view looking in the same direction and showing the thermostat and both valves in normal position, ready for 35 operation.

Fig. 3 is a front view of the gas valve.

Fig. 4 is a section through the piston looking in the same direction as Fig. 3.

Referring to said drawings: 1 indicates 40 the shell of the heater, 2 is the usual coil located within said shell, 3 is the usual burner or burners located immediately below said coil for heating water passing through the coil, 4 is a thermostat preferably placed in 45 the outlet of the lower section of the coil and may be of any of the usual types of construction, 5 is the water inlet which is led into the upper end of the water valve chamber 6. In said chamber is fitted a valve 7, to 50 open and close the port 8 and control the flow of water. A piston 9 is preferably placed in the chamber 6 although a separate chamber may be provided for it. The piston may be provided with a small relief 55 valve *r* or any equivalent means of preventing it from exerting excessive pressure on

the thermostat. The function of said relief valve is also to prevent or reduce to a minimum the possibility of the piston sticking in the lower part of the cylinder, in other 60 words, preventing the piston from sticking in an open position. This is preferably accomplished by fitting the piston 9 loosely on the valve stem 10. The water valve 7 is fastened to the upper end of this valve stem 65 and the collar 11 is also fastened to it a little farther down. The spring 12 bears against the collar 11 and holds the piston 9 and water valve 7 together so that normally they act as one piece in the usual 70 manner. The spring 12 is strong enough to overcome the spring 38 in the gas valve chamber, but is not so strong that when its effect is multiplied through the levers it might injure the thermostat. The lower 75 part of said valve stem 10 preferably passes through a stuffing box 13 in the lower end of the water valve chamber, and is connected to the levers hereinafter more particularly described.

In the lower end of the piston chamber 6, which, in the form illustrated, is also the water valve chamber, there is a small opening 14, a communicating passage 15, a small throttle valve 16, and a continuation of said 85 passage to an opening 17 into the hot water outlet pipe 18, all of which are arranged to allow the escape of and admission of water below the piston at any desired speed. The main port 8 communicates by means of the 90 pipe 19 with the inlet to the coil 2.

A thermostat may be placed outside the shell in which case the usual water circulation should be provided, to convey heat from the burners to the thermostat when no water 95 is flowing through the heater, but the thermostat is preferably placed inside the shell where it will be heated by the burners. One end of the thermostat communicates with the lower end of the coil and the other end 100 communicates with the hot water outlet 18. The thermostat may be of any of the usual types, but the parts should be strong because the strains are greater than in other heaters. The type shown in the drawings 105 has an outer tube 20 preferably of copper and an inner tube 21 preferably of the same material. The left end of the inner tube 21 is closed and the right ends of both tubes are securely fastened to a frame 22. Within 110 the inner tube is a porcelain rod 23 forced against the left end of the inner tube 21 by a

lever 24. The lower end of the lever 24 bears against an adjusting screw 25 and its upper end bears against a second lever 26. This second lever fulcrums on a knife edge 27 at its left end while its right end bears against an intermediate point of the floating lever 28. The left end of the floating lever 28 is flexibly and adjustably connected to the lower end of the valve stem 10 by means 10 of a pivot 29, a double link 30 and a nut 31 threaded on the valve stem 10. The link 30 is merely to permit the small transverse movements of the parts which occur when the device operates.

15 The right hand end of the floating lever 28 is connected to the lower end of the gas valve stem 32 by means of a pivot 33, a link 34 and a nut 35. A gas valve 36 is secured to the upper end of the valve stem 32 and is held against its seat 37 by gravity or by a spring 38.

A gas supply pipe 39 enters the upper chamber 40 and a gas pipe 41 conducts the gas from the lower chamber 42 to the 25 burners 3. A small gas pipe 43 conducts gas through a valve 44 to the pilot light 45. A screw stop 46 controls the amount of lift of the gas valve 36 and may be adjusted so as to limit the movement of the water valve 30 7 when the thermostat is cold. The movement of the piston 9 and through it the water valve 7 is also limited by the screw stop 47.

A frame 22 fastens all parts to the heater shell.

35 The operation is as follows:

The drawings show all parts in their normal positions as when no water is being drawn and all parts have become cool. Upon 40 opening any faucet on the hot water line 18, the water pressure is reduced in the small pipe 15 and in the lower part of the chamber 6 and the piston 9 will descend, the floating lever 28 pivoting on the end of the second thermostatic lever 26 will raise the gas valve 45 36 against the pressure of the spring 38 until stopped by screw 46. If the screw 46 is properly set and the thermostat remains below the predetermined temperature, port 8 will not be uncovered and little or no water 50 will flow from the faucet. This in particular differentiates my device from all others. The gas will now flow freely to the main burners and be ignited by the pilot light and combustion at maximum efficiency will 55 take place. As soon as the water reaches the predetermined temperature, the inner thermostat tube 21 will expand, and, the porcelain rod 23 being but little affected, will move slightly to the left, allowing the center of the floating lever 28 to move down and the water valve 7 to partly uncover the 60 port 8 so that a small amount of water will flow from the faucet. As the temperature increases, the port will be opened farther and 65 farther, delivering water at practically

uniform temperature, the quantity of water being automatically varied in accordance with the amount of heat produced by the burners. The burners will continue to burn at their full capacity and greatest efficiency, 70 which is not the case with other water heaters.

If the faucet is opened only part way or for any other reason the water does not flow as fast as it is heated, the gas valve automatically closes more or less so that there will be no great variation from the desired water temperature. In the arrangement of my invention in which the water valve 7 and piston 9 are in separate chambers, the 80 regulating or closing of the gas valve 36 is caused by the equalization of the water pressure on the two sides of the piston, due to the water valve entirely uncovering the main port at a time when only a small amount of 85 water is flowing. In the arrangement illustrated the gas valve is regulated partly as above described and partly by the direct action of the thermostat in lowering the floating lever 28 and allowing the spring 38 90 to close the gas valve 36 as far as may be required to keep the outflowing water at the desired temperature. In an extreme case the piston 9 and the water valve 7 may move down until they are stopped by the screw 47 95 and further heating of the thermostat would then lower the right end of the floating lever 28 and permit the gas valve 36 to close shutting off the gas.

At any time during the above described 100 operation, if the faucet is closed the pressures on the two sides of the piston 9 are immediately equalized allowing the spring 38 to move the piston 9 and water valve 7 upward sufficiently to close the gas valve 36. 105

If it is preferred that some water should flow from the faucet whether it has reached the desired temperature or not, it is only necessary to raise the stop screw 46 so that the initial movement of the piston will uncover the main port 8 to any desired extent. 110

I claim as my invention and desire to secure by Letters Patent:

1. In an automatic water heater, a burner 115 to heat the water, a valve to control the burner, a water motor to operate the valve, a balanced water valve so constructed that the water pressure in the opening direction is practically equal to the water pressure in 120 the closing direction, said balanced water valve being so located as to regulate and fully control the quantity of water heated, a thermostat responsive to the temperature of the water, and means operatively connecting 125 the thermostat with the balanced water valve.

2. In an automatic water heater, a coil for heating water under pressure, automatic means for heating the coil and the water 130

therein, a water chamber, a port therein, a valve adapted to close said port and prevent flow of water through said coil, and a thermostatic means adapted to operate said valve by moving it transverse to the direction of the water pressure to open said port in response to heat and establish a flow of water through said coil.

3. In an automatic water heater, a pipe 10 conveying the water to be heated, a burner for heating the water in the pipe, automatic means for bringing the burner into action when an outlet of the pipe is opened, a port through which the water passes, a valve 15 adapted to slide over said port and regulate the area of the water-way, a thermostat and means actuated thereby for operating said valve to regulate the flow of water from the pipe and proportion it to the capacity 20 of the burner.

4. In an automatic water heater, a water valve, means connected therewith to balance said water valve and make it independent of the water so that the force required to move it will be the same under all water 25 conditions, a thermostatic mechanism responsive to the temperature of the water and adapted to operate said valve, a burner for heating the water, and means for automatically bringing the burner into action.

5. In an automatic water heater, a coil 30 conducting water through the heater, a burner for heating said coil, means for bringing the burner into operation, a thermostat in a portion of the coil exposed to the heat of the burner, a valve adapted to regulate and completely control the flow of water through said coil, and means actuated by the thermostat for operating said valve.

6. In an automatic water heater, a burner to heat the water, a water motor to control the burner, a thermostat in a portion of the water which is directly exposed to the heat of the burner, and a water valve operated by 45 the thermostat and adapted to prevent the flow of cold water from the heater until the water has been heated by the burner to a predetermined temperature.

7. In an automatic water heater, a burner, 50 a thermostat in the heat zone thereof, means actuated by the thermostat for controlling the volume of water flowing from the heater and proportioning it to the capacity of the burner, and a water pressure operated device 55 for controlling the burner independent of the thermostat.

8. In an automatic water heater, having a casing, a burner within the casing to heat the water, automatic means for bringing the 60 burner into action, a thermostat inside the casing, and a water valve operated by the thermostat adapted to stop the flow of water from the heater while the water is below the predetermined temperature and to establish 65 a flow of water from the heater when the

water has been heated by the burner to the predetermined temperature.

9. In an automatic water heater, a burner to heat the water, a gas supply for the burner, a gas valve for the gas supply, a water motor to operate the gas valve, a water valve for regulating the temperature of the water independently of changes in the gas supply by varying the quantity of water coming within the heat zone of the burner, 70 and a thermostatic means responsive to the temperature of the water adapted to regulate the water valve in accordance with the temperature, both the water valve and the thermostat being adapted to operate independently of changes of water pressure and independently of the elasticity of the metal of which the parts are made.

10. In an automatic water heater, a cold water inlet pipe, a hot water outlet pipe, and 85 a thermostatic means so constructed that the stresses in the moving parts are independent of the water pressures adapted to regulate the water pressure in the hot water outlet pipe while the heater is in operation independent of the pressure in the cold water pipe and means for automatically supplying heat when the pressure in the hot water outlet pipe is less than that in the cold water 90 inlet pipe.

11. In an automatic water heater, a thermostat, a water valve adapted to operate independent of water flow and free from self moving tendency, said thermostat and water valve being operatively connected and adapted to compensate for changes in water pressure and automatic means for bringing the 100 heater into operation.

12. In an automatic water heater, a burner, a water motor, a gas valve actuated by said water motor, a water valve adapted to stop the flow of water through the heater, said water valve having no tendency to increase the size of opening therethrough with increase of difference of water pressure 110 thereon, and a thermostat adapted to operate said water valve.

13. In an automatic water heater, a water valve adapted to control the flow of water through the heater, a thermostat adapted to close said water valve when the water falls below a predetermined temperature, and means adapted to conduct heat to said thermostat when no water is flowing from the heater, a burner, and a water pressure operated means adapted to keep the burner 115 in full operation as long as a hot water outlet is open.

14. In an automatic water heater, a water motor, means operated thereby for supplying heat, a valve adapted to stop the flow of water from the heater, a thermostat independent of the water motor, and means operatively connecting the thermostat to the water valve to stop the flow of water when 125 130

cold and to establish the flow of water when hot.

15. In an automatic water heater, a burner for heating the water, means for automatically bringing the burner into action, a thermostat operative when no water is flowing, and a water valve operated thereby and adapted to prevent the flow of cold water from the heater and to establish a flow of water from the heater when the burner has heated the water to the predetermined temperature.

16. In an automatic water heater, a burner for heating the water, a water valve, a water motor operative when the water valve is closed adapted to automatically bring the burner into action upon the opening of a hot water outlet, a thermostat operative when no water is flowing, and means operated by the thermostat to open the water valve and establish a flow of water from the heater when the burner has heated the water to a predetermined temperature.

17. In an automatic water heater, a coil for heating the water, a burner for heating the coil and the water therein, a water pressure operated device for bringing the burner into action, a water valve, and a thermostat operative when the water valve is closed, for the purpose of opening said water valve when the burner has heated the water in the coil and of increasing and regulating the flow of water through the coil to the full capacity of the burner.

18. In an automatic water heater, a water valve, a thermostat responsive to the temperature of the water in the heater and operative when the water valve is closed, the water valve and thermostat being operatively connected and adapted to prevent flow of cold water from the heater and automatic means for supplying heat to the water in the heater.

19. In an automatic water heater, a water motor responding to the difference of water pressure upon opposite sides thereof, a gas valve operatively connected therewith, a thermostat responding to the temperature of the water, a water valve having no tendency to open with the flow, and means for operating said valve, the said means being actuated both by the water motor and the thermostat.

20. In a water heater, the combination of a water motor, a water valve for governing the flow of water positively, operated by said motor, and a thermostat for moving the water valve independent of the water motor.

21. In an automatic water heater, a water motor actuated by varying water pressure, a water valve, a metallic thermostat, the said water valve being actuated toward open position directly by the water motor, and by

the thermostat to a more open position to increase the flow of water corresponding to the increase in temperature in the water. 65

22. In an automatic water heater, a water motor, a water valve operatively connected to said water motor, and a thermostat adapted to limit the opening of said water valve by the water motor when below the predetermined temperature and permit it to open further as the temperature rises.

23. In an automatic water heater, the combination of heating means, means actuated by difference of water pressure for establishing a flow of fuel to the heating means and for establishing a limited flow of water through the heater, and means actuated by the temperature for regulating the amount of said flow of water through the heater in accordance with the capacity of the heating means and independently of the water pressure. 75

24. In a water heater, a movable member, a water valve, initially operated thereby, and temperature actuated means to automatically further open said valve to supply a proportionately greater volume of water to the heater commensurate with the increased elevation at which the water is drawn. 85

25. In a water heater, a burner, a gas valve, a water valve, a water motor, the initial movement of which opens the gas valve, and thermostatic means for automatically controlling the further movement in the same direction of said water motor to open the water valve. 95

26. In a water heater, a burner to heat the water, a thermostat, a water valve opened automatically by the joint action of a difference in water pressure and increase in temperature of the water, in combination with a fuel valve opened by the joint action of said difference in water pressure and decrease in temperature of the water. 100

27. In a water heater, a fuel valve, a water valve, a difference of water pressure controlled means to open the fuel valve and tend to open the water valve, and a temperature controlled means to open said water valve in response to heat and to tend to close said gas valve. 110

28. In a water heater, the combination of a water valve, a gas valve, and a thermostatic means for moving one of said valves in the opening direction and the other of said valves in the closing direction. 115

29. In an automatic water heater, a thermostat, a gas valve and a water valve interconnected by a lever, the said lever having three bearing points connected respectively to the thermostat, gas valve and water valve, so that each of the three bearing points, at any instant when it is stationary, 120

125

acts as a fulcrum to enable a second to actuate the third.

30. In an automatic water heater, a water motor, a thermostat and a gas valve operatively interconnected, and a power device for holding the water motor, gas valve and thermostat in normal position.

31. In an automatic water heater, a water motor, a thermostat and a water valve, operatively interconnected, and a power device for holding said water motor, thermostat and water valve in normal position.

32. In an automatic water heater, a thermostat, a water valve and a gas valve, interconnected, and a power device for hold-

ing said thermostat, water valve and gas valve in normal position.

33. In a water heater, a thermostatic means for automatically controlling the flow of water through the heater, and means for 20 converting said thermostatic means into means for automatically controlling the flow of gas.

In testimony whereof I have hereunto signed my name in the presence of two sub- 25 scribing witnesses.
